UNITED STATES PATENT OFFICE.

OTTO A. KRENKE, OF PORT HURON, MICHIGAN, ASSIGNOR TO ANKER-HOLTH MANUFACTURING CO., OF PORT HURON, MICHIGAN, A CORPORATION OF MICHIGAN.

CREAM-SEPARATOR.

1,256,577.

Specification of Letters Patent. Patented Feb. 19, 1918.

Application filed June 15, 1916. Serial No. 103,709.

To all whom it may concern:

Be it known that I, Otto A. KRENKE, a citizen of the United States, residing at Port Huron, county of St. Clair, State of Michigan, have invented a certain new and useful Improvement in Cream - Separators, and declare the following to be a full, clear, and exact description of the same, such as will enable others skilled in the art to which it pertains to make and use the same, reference being had to the accompanying drawings, which form a part of this specification.

This invention relates to an automatically controlled feed for the milk of a cream separator. It comprises a governor arranged to allow the milk to enter the cream separator when a predetermined speed of the revolute element of the cream separator has been reached, and also to shut off the feed of milk when the speed of the revolute element falls below the predetermined speed or materially exceeds the predetermined speed.

It is necessary for the proper operation of a cream separator which works upon the centrifugal force principle that the machine be operated at the speed which it was designed for, for it will be obvious that the increase or decrease of the speed above or below a given point changes the centrifugal force and makes the operation of the machine and its separating functions wholly unreliable. This has long been known and it has been overcome by the use of devices which indicate the speed of the revolving element and which are consulted by the operator before and while the milk is fed into the separator. Of course any machine depending upon human operation is subject to the frailty and the uncertainties of human vigilance. It is the object of my invention to do away entirely with the human element and to make the machine entirely automatic. To this end I have devised the mechanism hereinafter to be described.

In the drawings,—

Figure 1 is a side elevation of the cream separator with the control apparatus and a portion of the receptacle, some of the parts being sectioned for clearness of illustration.

Fig. 2 is a detail of the driving connections.

Fig. 3 is a detail of the connection between the cut off valve and the governor.

Fig. 4 is a detail of the pivot that I use to 55 make the walking beam detachable.

The cream separator is designated *a*. Its details of construction and its mode of operation need not be detailed. Suffice it to say that it is the ordinary separator operated upon the centrifugal principle. The large driving gear is designated *b* and to this is connected the driven pinion *c* carried upon a shaft which has on its opposite end a beveled driving pinion *d* which meshes 60 with the beveled driven pinion *e*. This is on the lower end of a vertical shaft journaled in a yoke *f* and below the top of the yoke the shaft is provided with a sleeve *g* which is fast thereto. Near the lower end of the 65 yoke the shaft is provided with a slip sleeve *h*. To each of these sleeves is pivoted a pair of links *i* and the upper links have on their ends the weighted balls *j* forming the well known centrifugal governor. The spiral 70 spring *k* tends to space the two sleeves apart and resist the tendency to throw out caused by rapid rotation of the balls. The upper part of the shaft is screw-threaded and the adjusting nut and lock nut *l* are located on 75 this threaded portion so that the pressure of the spring may be adjusted to regulate the spring pressure and determine the speed of the revolute element necessary to overcome the spring pressure and throw the balls out. 80

The slip sleeve *h* is provided with a half spherical terminal which provides an upwardly directed circular face upon which runs the end of a lever *m* which is held to this face by the small spiral spring *n*. This 85 lever *m* is provided at its outward end with a vertical extension *p* which is screw-threaded at its end to receive the two nuts *o* which adjustably connect it with the walking beam *q*. This walking beam *q* is pivoted on an 90 upright *r* by the pivot *s*. The outer end of the walking beam is bifurcated and straddles the pivot pin *t* carried on the end of the valve stem *u*.

The milk is contained in the receptacle *v*, 100 which is provided with an outflow pipe *w* whose end is shaped to provide a tapered valve chamber *x* adapted to receive a turn-plug valve *y* which has a chambered center and when turned as shown in Fig. 1 communicates with the outflow passage-way *w* and discharges through the opening in the bottom of the valve. It will be obvious that 105

this turn-plug valve may be used to entirely cut the flow off by turning the side opening around to the position of non-registry with the out-flow passage *w*. This may be done 5 by the hand as the top of the valve is provided with a wing *z* for this purpose. Below the turn-plug valve the valve chamber *w* extends some distance to form a puppet valve chamber 1 in which the puppet valve 10 2 functions. When this puppet valve is raised to the limit of its upward movement it closes the opening in the bottom of the turn-plug valve. When it is dropped it seats upon the valve seat about the final 15 outflow opening in the valve chamber *w*. It will, therefore, be understood that ordinarily the valve 2 seats upon the rim of the outflow opening in the valve chamber *w* and consequently prevents the flow of the milk 20 into the cream separator *a*. Now, when a predetermined speed has been reached in the rotation of the revoluble element in the cream separator *a*, the balls *j* of the governor overcome the pressure which has been 25 given the spring *h* by adjusting the nuts *l*, and the balls throw out, thereby raising the slip sleeve *h*, the contact end of the lever *m*, pulling down the opposite end of the lever, and consequently the left hand end of the 30 walking beam *q*, thereby raising the valve stem *t* and the puppet valve 2 from its seat to such a position as is shown in Fig. 1. In this position the milk may freely flow into the cream separator. When the predetermined speed is materially exceeded, the balls 35 continue to throw out and the puppet valve continues to rise until it reaches the opening in the bottom of the turn-plug valve and seats thereupon and completely closes 40 off the flow of the milk. In this position the valve remains until the proper speed of the revoluble element has again been reached.

It will be noticed that the walking beam 45 is arranged so that it may be easily removed from the devices attached to the milk receptacle so as to allow the milk receptacle to be removed. The walking beam is pivoted upon a handle-provided pivot *s* which 50 is detailed in Fig. 4 and shown in Fig. 3. The pivot is provided with two flat sides so that when the handle is turned parallel with the walking beam, the walking beam may be slipped over the flat sides of the 55 handle-provided pivot, the latter passing through the aperture 3 in the side of that portion of the walking beam which engages around the pivot opening. This allows the bifurcated end of the walking beam to be 60 drawn away from the pivot *t* so that the milk receptacle together with the devices it carries can be removed from the cream separator and the governor apparatus. It is also noted that the walking beam is provided with a hooked portion 4 on its lower 65

side facing the aperture 3 so that this hooked portion may be slipped over the handle-provided pivot *s* to temporarily hold the walking beam during the absence of the milk receptacle.

70

What I claim is:

1. In a liquid-feeding governor, the combination of a centrifugal liquid separator, a feed line thereto, and means for automatically controlling the flow through the feed line so that the flow of fluid is not permitted until a predetermined speed of the liquid separator has been attained and which precludes the flow of the liquid when excessive speed of the liquid separator is attained.

75

2. In a liquid-feeding governor of the character described, the combination of a centrifugal liquid separator, a feed line leading thereto, an inlet valve for controlling the feed line, and means governing said valve for allowing the flow only when a predetermined speed has been reached by the revoluble element of the centrifugal separator, and said means further closing off the flow when said predetermined speed has been materially increased or decreased.

85

3. In a governor-controlled valve, an out-flow pipe provided on its end with a terminal open at top and bottom forming a valve chamber, a turn-plug valve having a chambered center open at its lower end and communicating with the exterior through one side, said turn-plug valve being adapted to allow the discharge of fluid therethrough when the side opening in the same registers with the passage-way in the outflow pipe, a puppet valve located in the space between the lower end of the turn-plug valve and the valve chamber and governing the opening at the bottom of the turn-plug valve and the opening at the bottom of the valve chamber, and a governor for automatically operating said puppet valve when a revoluble element attains certain specified speeds.

95

4. In a governor-controlled valve, an out-flow pipe, a valve and valve stem for controlling the flow through the outflow pipe, and apparatus for automatically operating said valve in accordance with the speed of a revoluble element, said apparatus including a walking beam supported upon an upright by a handle-provided pivot having flat sides which allows escape through the cut away portion of that portion of the walking beam which surrounds the pivot as a wall, and the end of the walking beam being provided with a bifurcated end which allows the same to be withdrawn from a pivot on the valve stem which the bifurcated end straddles.

100

5. In a governor-controlled valve, an out-flow pipe, a valve and valve stem controlling the outflow pipe, and apparatus for controlling the operation of the valve in accordance with the speed of a revoluble element and in-

110

115

130

cluding a walking beam supported upon an upright by a handle-provided pivot having flat sides which allows the escape of the walking beam through a recess in the portion of the walking beam which surrounds the pivot as a wall and the walking beam being provided with a bifurcated end which straddles a pivot pin on the end of the valve stem, and the said walking beam further being provided with a hooked portion whose opening faces the opening through which the pivot pin of the upright may escape and which allows the walking beam to be temporarily rested within the hooked portion of the said handle-provided pivot.

6. In a liquid-feeding governor of the character described, the combination of a centrifugal liquid separator, a feed line leading thereto and provided with a pair of valve seats, a single puppet valve, and governor apparatus for causing the puppet valve to seat on one of the valve seats until a predetermined speed is reached and upon the attainment of excessive speed to seat upon the other valve seat, thereby to maintain a proper speed of the liquid separator. 20 25

In testimony whereof, I sign this specification.

OTTO A. KRENKE.
